UNITED STATES PATENT OFFICE.

JOHN H. SMITH, OF DUBUQUE, IOWA.

DESIGN FOR A DESK FOR HOTEL-REGISTERS.

No. 39,872.

Specification for Design.

Patented March 9, 1909.

Application filed June 10, 1908. Serial No. 437,764. Term of patent 3½ years.

To all whom it may concern:

Be it known that I, JOHN H. SMITH, a citizen of the United States, residing at Dubuque, in the county of Dubuque and State of Iowa, have invented a new, original, and ornamental Design for Desks for Hotel-Registers, of which the following is a specification, reference being had to the accompanying drawing, forming part thereof.

The figure is a perspective view taken from the front side, showing my new design.

I claim:

The ornamental design for a desk for hotel registers, as shown.

JOHN H. SMITH.
